UNITED STATES PATENT OFFICE

125,269

DESIGN FOR A LATHE

William F. Groene, Cincinnati, Ohio, assignor to
The R. K. Le Blond Machine Tool Company,
Cincinnati, Ohio, a corporation of Delaware

Application January 29, 1940, Serial No. 89,867

Term of patent 14 years

To all whom it may concern:

Be it known that I, William F. Groene, a citizen of the United States and a resident of Cincinnati, in the county of Hamilton and State of Ohio, have invented a new, original, and ornamental Design for a Lathe, of which the following is a specification, reference being had to the accompanying drawings, forming part thereof.

Fig. I is a front perspective view of a lathe embodying my new design.

Fig. II is a rear perspective view of the lathe shown in Fig. I.

Fig. III is a front tailstock end perspective view of the lathe.

Fig. IV is a rear tailstock end perspective view of the lathe.

Fig. V is a rear headstock end perspective view of the lathe.

Fig. VI is an enlarged view of a portion of Fig. I for the purpose of more clearly showing the design of the headstock and feed box arrangement of the lathe.

I claim:

The ornamental design for a lathe, substantially as shown.

WILLIAM F. GROENE.
